US00D864154S

(12) **United States Design Patent** (10) **Patent No.:** **US D864,154 S**
Hu (45) **Date of Patent:** **** Oct. 22, 2019**

(54) **HEADPHONE**

(71) Applicant: **SHENZHEN QIANHAI PATUOXUN NETWORK AND TECHNOLOGY CO., LTD**, Shenzhen (CN)

(72) Inventor: **Zaihui Hu**, Shenzhen (CN)

(73) Assignee: **SHENZHEN QIANHAI PATUOXUN NETWORK AND TECHNOLOGY CO., LTD**, Shenzhen (CN)

(**) Term: **15 Years**

(21) Appl. No.: **29/688,685**

(22) Filed: **Apr. 23, 2019**

(30) **Foreign Application Priority Data**

Oct. 26, 2018 (CN) 2018 3 0599989
(51) **LOC (12) Cl.** **14-01**
(52) **U.S. Cl.**
USPC **D14/205**

(74) Attorney, Agent, or Firm — JCIP Global Inc.

(57) **CLAIM**

The ornamental design for a headphone, as shown and described.

DESCRIPTION

FIG. 1 is a perspective view of a headphone showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines immediately adjacent the shaded areas represent the bounds of the claimed design, while all other broken lines are directed to environment and are for illustrative purposes only; the broken lines form no part of the claimed design.

1 Claim, 7 Drawing Sheets
